UNITED STATES PATENT OFFICE.

JAMES E. COCHRANE, OF PONTIAC, MICHIGAN.

DESIGN FOR A WAGON-BODY.

SPECIFICATION forming part of Design No. 34,516, dated May 14, 1901.

Application filed January 21, 1901. Serial No. 44,228. Term of patent 7 years.

To all whom it may concern:

Be it known that I, JAMES E. COCHRANE, a citizen of the United States, residing at Pontiac, county of Oakland, State of Michigan, have invented and produced a certain new and original Design for Wagon-Bodies; and I declare the following to be a full, clear, and exact description of the same, reference being had to the accompanying drawings, which form a part of this specification.

Figure 1 is a perspective view of the wagon-body, showing my new design. Fig. 2 is a longitudinal section, and Fig. 3 is a cross-sectional view of the body.

15 Similar letters refer to similar parts.

As shown in the drawings, the side of the body consists of two sunken panels A B with rounded ends and located end to end.

As shown in the drawings, the rectangular 20 side of the wagon-box body is formed with two rectangular equal sunken panels A B with rounded ends and located end to end

and having an intermediate raised portion between them, as shown in Figs. 1 and 2, and having the cross-section shown in Fig. 3. The 25 panels A B are formed by a raised work C around the sunken portions D D.

The leading material feature in my design for a wagon-body consists in the two equal sunken rounded end panels symmetrically 30 arranged with reference to the rectangular shape of the side of the wagon-body, the two panels being surrounded and separated by raised work C C.

Having thus described my invention, what 35 I desire to claim is—

The design for a wagon-body as herein shown and described.

In testimony whereof I sign this specification in the presence of two witnesses.

JAMES E. COCHRANE.
